UNITED STATES PATENT OFFICE.

DIXON HY. DAVIES, OF LEEDS, COUNTY OF YORK, AND JOHN M. TOURTEL,
OF WESTMINSTER, COUNTY OF MIDDLESEX, ENGLAND.

TOLL APPARATUS FOR PRODUCING ELECTRIC LIGHT.

SPECIFICATION forming part of Letters Patent No. 395,215, dated December 25, 1888.

Application filed July 11, 1888. Serial No. 279,648. (No model.) Patented in England June 7, 1887, No. 8,206; in France April 7, 1888, No. 189,828, and in Belgium April 7, 1888, No. 81,335.

To all whom it may concern.

Be it known that we, DIXON HENRY DAVIES and JOHN MESNY TOURTEL, subjects of the Queen of Great Britain, residing, respectively, at 88 Caledonian Road, Leeds, in the county of York, England, and at 3 Prince's Street, Westminster, in the county of Middlesex, England, have invented a new and useful Apparatus for Effecting by Introduction of a Coin the Production of Electric Light for a certain time, (for which we have obtained patents in Great Britain, dated June 7, 1887, No. 8,206, and have made application for patent in Great Britain, dated April 7, 1888, No. 5,201, which patent when granted will bear date April 7, 1888, No. 5,201; in France, dated April 7, 1888, No. 189,828, and in Belgium, dated April 7, 1888, No. 81,335,) of which the following is a specification.

This invention has for its object to provide a simple and novel apparatus (more especially designed for railway-carriages and other vehicles, but applicable to other purposes) whereby a passenger or person can obtain an electric light for a given length of time by inserting a coin into the apparatus and continue the light for a longer time by successively contributing coins.

To such end the invention consists in the features of construction and combination of devices hereinafter described and claimed, reference being made to the accompanying drawings, in which—

Figures 1, 2, 3, and 4 of the accompanying drawings are vertical sections of apparatus according to our invention, showing different phases of its action. Fig. 5 is a sectional plan.

A box is divided by partition C into two compartments, A, which contains an incandescent electric lamp, L, and B, which in its upper part contains the mechanism, its lower part serving as a receptacle for the coins. In the cover M of the box there is a slot, S. A coin introduced through S drops into a swinging pocket, D, which, as well as a lever, F, is pivoted at E. A lip, G, at the end of the lever F, in the position, Fig. 1, serves as a bottom to the pocket D, the coin resting on G. A

spring, J, acting on an arm, K, of the lever F, presses a shoulder, I against a plate, N.

P is a push, having cross-pins R R', against which press two blade-springs, Q Q', keeping P in the position shown in Figs. 1 and 5, the cross-pins R R' then bearing against another spring, T. The upper part of the pocket D is sufficiently open to permit the push P to be thrust inward without moving the pocket; but when a coin of the proper value is dropped into D the push, bearing against the upper part of the coin, causes the pocket D to move about its pivot E, carrying with it the lever F. When the pocket D is thus moved, a nose, U, projecting from it, moves a switch-lever, a, and another nose, V, moves a clock-lever, b, shifting these levers to the position shown in Fig. 2. The switch-lever a is thus brought against a contact-piece, c, closing an electric circuit and kindling the lamp L, the clock-lever b winding a clock-spring and moving a ratchet-wheel, e, fixed to b. A pawl, f, pivoted upon a wheel of the clock-work d, catches in the teeth of the ratchet e, and thus the lever is engaged with the clock-work and moves slowly back as the clock-work runs down.

t' is an electro-magnet, the coils of which are in the lamp-circuit. At the back of the lever F is an armature, h, attached by a spring, g, so that when the lever F is moved back the armature h is first pushed up to the poles of the electro-magnet t', and then the switch-lever a closes the circuit. The magnet being thus excited, holds the armature h and retains the lever F in opposition to the spring J after the push P is released and moved back by the springs Q Q'. The pocket D, being now free, drops by gravity to the position shown in Fig. 2, and, as its bottom is open, the coin falls into the coin-receptacle below. The clock-work d slowly runs down, moving back the lever b, which eventually, bearing against a stud, i, on the lever a, moves a off the contact-piece c, thus opening the circuit and extinguishing the light and at the same time rendering the electro-magnet t' inert. The armature h being no longer attracted, the lever F is moved back by the spring J, moving back also the pocket

D to the position shown in Fig. 1, the lever *b* resting against a stop, *n*, and the mechanism being ready for a fresh operation. Should there be from any cause a failure of electricity, so that upon a coin being introduced and the push *P* being operated no light appears, the electro-magnet *t t'* remains inert and cannot hold back the lever *F*, which consequently returns with the pocket *D* into its original position, as in doing so *F* is arrested by coming in contact with the chute *N*, while *D*, owing to the momentum it has attained, swings farther forward, thereby uncovering its opening and allowing the coin to drop into the passage *l*, so as to be returned to the operator at the mouth *m*, so that he will get back his coin when the light fails to appear.

The depth of the pocket *D* below the push *P* is such that if the coin introduced is smaller than that required the push *P* passes above the coin, but moves the lever *F* a little backward sufficiently to withdraw the lip *G* from beneath the pocket *D*, as shown in Fig. 4, allowing the coin to drop into the passage *l* and to be returned to the operator.

Although we have shown the pocket *D* and the lever *F* pivoted on a horizontal axis, they might obviously be pivoted on an axis vertical or inclined.

Having thus described the nature of our invention and the best means we know of carrying it out in practice, we claim—

In an apparatus for producing an electric light by the deposit of a coin, the combination of an electro-magnet, an electric contact, clock-work, an incandescent lamp, and an electric current, with a pivoted swinging pocket for receiving the deposited coin, a push-button which by its inward thrust closes the circuit and acts directly on the coin in the pocket and swings the latter inward, and a pivoted coin retaining and releasing lever which swings inward with the pocket toward the electro-magnet when the push-button is thrust inward, substantially as described. 35 40 45

In testimony whereof we have signed our names to this specification, in the presence of two subscribing witnesses, this 20th and 23d day of June, A. D. 1888.

DIXON HY. DAVIES.
JOHN M. TOURTEL.

Witnesses to signature of Dixon Henry Davies:

C. GILLIARD,
Clerk at U. S. Consulate, Leeds.

A. DENNELL,
Messenger at U. S. Consulate, Leeds.

Witnesses to signature of John Mesny Tourtel:

ALFRED GUERN,
Of Guernsey, Solicitor.

JAMES C. LAFERTEY,
Of Guernsey, Law Agent.
